UNITED STATES PATENT OFFICE.

PETER F. WEBER, OF COLUMBUS, INDIANA.

IRONING-BOARD.

SPECIFICATION forming part of Letters Patent No. 287,596, dated October 30, 1883.

Application filed March 24, 1883. (No model.)

To all whom it may concern:

Be it known that I, PETER F. WEBER, a citizen of the United States, residing at Columbus, in the county of Bartholomew and State 5 of Indiana, have invented certain Improvements in Ironing-Boards, of which the following is a specification.

My invention relates to an ironing-board especially adapted for holding the neckband 10 and bosom of a shirt during the process of ironing the same.

The objects of my improvements are, first, to provide a means for holding the neckband of the shirt smoothly and at a suitable angle with 15 the front of the shirt; second, to provide an improved means for straightening and holding securely the bosom of the shirt; third, an improved means for securing a cloth covering on the central portion of the board, all as hereinafter more fully described. I attain these 20 objects by means of the following-described mechanism, which is illustrated in the accompanying drawings.

Figure 1 represents a plan view of my ironing-board; Fig. 2, a side elevation; Fig. 3, a cross-section on the line $x-x$; Fig. 4, a similar section on the line $z-z$, showing the cloth covering in position.

The board a is of suitable size and shape to 30 be inserted within the body of a shirt. A groove, b , is formed in the upper surface of the board, leaving a central portion, c , having semicircular ends, as shown. The sides of groove b do not form right angles with the 35 surface of the board, but slant outward toward the edges of the board, as shown in Fig. 3.

For the purpose of securing a cloth covering to the central portion, c , of the board, a second groove, e , Fig. 3, is formed in the side 40 of groove b , said groove e being inclined inward all round c , and the corners of c being rounded, as shown at $f-f$. The cloth covering is spread over the surface of c and there secured by a wire, h , drawn tightly around the 45 overhanging edges and into the groove e , as shown in Fig. 4. To the top surface of c an extensible ring, d , is secured. Said ring is slightly larger in diameter at the top, making its sides slightly flaring, and is formed of a 50 thin strip of sheet metal, the ends overlapping and adapted to slide one upon the other. A

spring-catch, i , fastened to one of the overlapping ends and entering any one of a series of holes, $j-j$, in the other, fastens the ends in any desired relative position. Holes $j-j$ may 55 have numbers opposite them on the inside of the ring, indicating the number of inches in the circumference of the ring.

Ring d is secured to the board in the following manner: The side opposite the overlapping ends is fastened in a fixed position to the board by screws or staples driven through eyes w on the ring. For the purpose of securing the other side of the ring to the board in different positions as the ring is expanded or contracted, a block, k , is fitted to slide in a slot, l , in a plate, m , which is fastened permanently to the surface of the board. The edges of the slot in plate m enter suitable grooves in the sides of block k , as shown in Fig. 3, 70 so that the block is free to slide longitudinally thereon, but cannot be separated therefrom. A stud, n , passes through a slot, o , in the side of the ring, and is fastened into the end of block k , thereby holding that side of the ring 75 down to the board, but allowing the size of the ring to be adjusted to suit different-sized neckbands by sliding block k in slot l . A spring catch or pin, p , on the inner end of block k engages either one of a series of holes, 80 r , in the plate, which holes are numbered to indicate the length in inches of the circumference of the ring.

For the purpose of confining the shirt-bosom upon the board and stretching it smoothly 85 thereon, a clamp, s , formed of spring-wire, and of a general outline corresponding to the groove b , and having a handle, t , formed thereon, is hinged to board a at u . Said clamp is curved upward, and when in its normal position stands as shown in Fig. 2.

The operation of my device is as follows: The ring d is adjusted to the required circumference to fit the neckband of the shirt to be ironed, which circumference is indicated by 95 the position of the block k , as before described. The shirt is now slipped over the board, and the neckband fastened smoothly around ring d by passing the button-holes therein over stud n . The handle of clamp s is now seized 100 by the operator and the clamp brought down on the shirt-front, being drawn downward to-

ward the foot of the board at the same time, which has the effect of elongating and narrowing the clamp, so that its sides lie on top of *c*. The end of the clamp held by the operator is 5 now quickly thrust inward, and the clamp is thereby spread in the direction of its width. It then slips down over the sloping sides of groove *b*, and draws the shirt-bosom smoothly outward in all directions. The handle of the 10 clamp now enters a notch, *v*, cut in the board down to the bottom of groove *b*, and the recoil of the spring-wire of which the clamp is formed forces it outward under the outer edge of the groove *b*, thereby holding it down. 15 The shirt-bosom may now be ironed in the usual manner, and the neckband may be

nicely smoothed and shaped by pressing it with the iron against and around ring *d*.

I claim as my invention—

1. The combination of an ironing-board 20 having groove *b*, inclined outward and downward, and the spring-clamp *s*, hinged to said board, substantially as shown and described.

2. The combination, with an ironing-board, of adjustable ring *d*, sliding block *k*, plate *m*, 25 and means for securing said block in different positions on said plate, substantially as and for the purpose set forth.

PETER F. WEBER.
